UNITED STATES PATENT OFFICE.

BERNARD HAUSMANN, OF NEW YORK, N. Y., ASSIGNOR TO B. HAUSMAN COMPANY, INC., OF NEW YORK, N. Y., A CORPORATION OF NEW YORK.

WINDOW.

1,331,342.

Specification of Letters Patent.

Patented Feb. 17, 1920.

Application filed March 25, 1918. Serial No. 224,468.

To all whom it may concern:

Be it known that I, BERNARD HAUSMANN, a citizen of the United States, residing in the borough of Manhattan of the city of New York, in the State of New York, have invented certain new and useful Improvements in Windows, of which the following is a specification, reference being had to the accompanying drawings, forming a part

hereof.

This invention relates to windows of the type known as double-hung, in which the sash or each sash may slide vertically and may also swing inward to a greater or less extent for the purpose of permitting ventilation without draft and also for permitting the cleaning of the window on both sides, without requiring the cleaner to stand outside the window. Various forms of double-hung windows have been devised, all requiring window fittings or hardware of a considerably expensive nature. The present invention has for its general purpose to provide means whereby a double-hung sash can be supported and operated with fittings or hardware much less expensive than that commonly employed and thereby reducing largely the factor of cost which hitherto has prevented the more general use of double-hung windows. In accordance with the invention the supporting chain at each side of the window, to which the counterbalance weight is connected at one end, is connected at the other end to the sash, preferably by a long link or arm which may be regarded as part of the supporting chain, and is provided, at a suitable point above the point of attachment to the sash, with a device which, as soon as the inward swinging movement of the window begins, engages a device fixed to the frame or casing so that the sash is then locked against vertical movement. Means are also provided whereby the inward swinging movement of the sash can take place only when the sash is at or near its lowest position. The invention will be more fully explained hereinafter with reference to the accompanying drawings in which it is illustrated, and in which—

Figure 1 is a view in vertical section of a window which embodies the invention, the sash being shown as swung inward.

Fig. 2 is a detail view in perspective, and in section through the casing, on a larger scale than that of Fig. 1, a portion of the lower sash being broken out.

Fig. 3 is also a detail view in perspective illustrating particularly the relation of the locking devices of the two sashes to the frame or casing of the window.

Figs. 4 and 5 are detail views illustrating a modification to be described.

In the embodiment of the invention illustrated in Figs. 1, 2 and 3 of the drawings, the lower sash *a* and the upper sash *b* are arranged to slide as usual in a casing *c*. In the present instance, in order that the upper sash *b* may swing inward when in its lowest position, the head of the casing, as at *c'*, is arranged to receive the top of the lower sash, so that when the lower sash is raised to its highest position the upper sash, then in its lowest position, may swing under the other sash. Each sash slides as usual in its own track. The track for the lower, or inner, sash may have no inner stop bead in its lower half or in its upper half, a stop *d*, having a movable member *d'*, being provided just above the plane of the top of the inner sash when in its lowest position and serving to prevent the inner sash from moving bodily inward when in any position above the lowest and serving also, through the movable member *d'*, to prevent the swinging inward of the inner sash when in its lowest position unless such inward swinging movement is desired. The track for the upper or outer sash has a stop bead *c²* in its upper half, to prevent the sash from moving inward except when in its lowest position, but the lower half of the track may have no stop bead at all, or a movable stop bead, so that the outer sash is free to be swung inward when in its lowest position.

Each sash chain or cord *e*, connected at one end to a counterbalance weight, not shown, passes over a pulley *c³* and is connected to the sash at a point preferably below the middle of the sash. The casing and the sash are formed so as to receive the chain between them as usual. Preferably each chain or cord is connected to the sash through a link or arm *e'* which may be regarded as a part of the chain or cord. The arm or link is pivotally connected at its lower end to the sash, as at *e²* near the middle of its vertical side, and is also pivotally connected, as at *e³*, to the flexible portion of the chain or cord. To the chain, at a suitable distance above the point of attachment to the sash and near the top of the sash, is secured a device or one member

of a device which may coöperate with a corresponding device or member of a device fixed to the casing, for the purpose of locking the sash against upward movement when the inward swinging movement of the sash has commenced. As shown in Figs. 1, 2 and 3, the pivot pin e^3 is extended from the chain toward the casing and is preferably provided with a head e^4 , and a plate f , notched as at f' , is fixed to the casing c .

As shown in Figs. 4, and 5, the arm or link e' might be notched, as at e^5 , and a pin f^2 be carried by the plate f .

15. A stop g , having a movable member g' , secured to the main part g by a screw and slot connection, as clearly shown in Fig. 2, is secured to the casing c in such position that when the movable member g' is pulled out, as shown in Figs. 1 and 2, the movable member stands in the path of the sash a and prevents the same from swinging inward, while if the movable member g' is pushed up, above the top of the sash a , then the 25 sash can be swung inward.

When either sash is in its lowest position and vertical, there is no engagement of the members of the locking device and the sash may then be raised. When, however, 30 the sash is in its lowest position and the inward swinging movement of the sash is commenced, the lower end of the chain or of the arm or link, as the case may be, moves inward with the sash and carries 35 the corresponding member of the locking device into engagement with the other member of the locking device, so that shortly after the inward swinging movement of the sash is commenced, the sash or rather the 40 chain which supports the sash is locked against upward movement. It is therefore impossible to move the sash bodily upward when it has been swung inward. While the 45 chains at the two sides of the sash are thus locked against vertical movement, the sash can be swung inward to an extent permitted by the arm or link e' , or the portion of the chain between the points e^2 and e^3 . The bottom of the sash then rests substantially 50 on the sill of the window, as shown in Fig. 1.

When the sash is swung back to vertical position the locking device is disengaged as the lower part of the chain or the arm or link returns to a vertical line, and the sash 55 can then be raised.

It will be understood that the usual weather beads and grooves may be provided, the same being arranged to permit each sash to swing inward. It will also be understood 60 that various changes in details of construction and arrangement may be made to suit different conditions of use and that the invention, except so far as pointed out in the

accompanying claims, is not limited to the particular construction and arrangement shown and described herein. 65

I claim as my invention:

1. In a window the combination of a casing, a sash free to slide vertically in the casing free to swing inwardly, and free from connection with the casing at its lower end, a chain secured at its lower end to the sash near the middle of the vertical side, one member of a locking device secured to the chain at a distance above the point of attachment near the top of the sash and another member of the locking device definitely located on and secured to the casing, the two members of the locking device being adapted to be brought into positive locking engagement to prevent upward movement of the sash when it is swung inward. 75

2. In a window the combination of a casing, a sash free to slide vertically in the casing free to swing inwardly, and free from connection to the casing at its lower end, a chain, an arm or link forming an extension of the chain and pivotally secured at its lower end to the sash near the middle of the vertical side, one member of a locking device carried by the arm at its upper end near the top of the sash and another member of the locking device definitely located on and secured to the casing, the two members of the locking device being adapted to be brought into positive locking engagement to prevent upward movement of the sash when it is swung inward. 85

3. In a window the combination of a casing, a sash free to slide vertically in the casing and free to swing inwardly, a chain secured at its lower end to the sash, one member of a locking device secured to the chain at a distance above the point of attachment, another member of the locking device secured to the casing, the two members of the locking device being adapted to be brought into locking engagement to prevent upward movement of the sash when it is swung inward, and a stop to prevent the inward swinging of the sash but movable to permit the same only when the sash is in its lowest position. 100

4. In a window the combination of a casing, a sash free to slide vertically in the casing free to swing inwardly, a chain secured at its lower end to the sash near the middle of the vertical side, and locking means near the top of the sash brought into locking relation by the inward movement of the chain 115 to prevent the upward movement of the sash, comprising a locking member definitely located on the casing. 120

This specification signed this 19th day of March, 1918. 125

BERNARD HAUSMANN.
